UNITED STATES PATENT OFFICE.

JOSEPH HARDING, OF ROCHESTER, NEW YORK.

DESIGN FOR A SHOE.

SPECIFICATION forming part of Design No. 29,909, dated December 27, 1898.

Application filed November 29, 1898. Serial No. 697,798. Term of patent 3½ years.

To all whom it may concern:

Be it known that I, JOSEPH HARDING, a citizen of the United States, and a resident of Rochester, in the county of Monroe and State 5 of New York, have invented a certain new and original Design for Shoes, of which the following is a full, clear, and exact description.

Figure 1 is a perspective showing my new design, and Fig. 2 is a sectional view of a portion of Fig. 1.

As shown in the drawings, the leading feature of my design consists of a series of braided bands 1, joining the shanks of buttons 2, said buttons being arranged in diverging rows, 15 one on each side of a middle line of the closed shoe-upper. The distance between the connected buttons increases from top to bottom, as shown. The said bands or pieces of braid cross the front of the shoe-upper at right an-

gles to its longitudinally central line and extend between the buttons, as indicated. The shoe-upper comprises two parts 3 and 4, joined by a third part 5, said part 5 closing the space between parts 3 and 4, which space is bridged by the bands, terminating at a button in each 25 direction.

Having described my invention, what I claim as new, and desire to secure by Letters Patent, is—

The design for a shoe as herein described 30 and shown.

In testimony whereof I have signed this specification in the presence of two subscribing witnesses.

JOSEPH HARDING.
